UNITED STATES PATENT OFFICE.

WILLIAM CURTIS LINDER, OF ANTONIA, LOUISIANA.

FRAME CONSTRUCTION.

1,092,727.

Specification of Letters Patent. Patented Apr. 7, 1914.

Application filed September 6, 1912. Serial No. 718,976.

To all whom it may concern:

Be it known that I, WILLIAM C. LINDER, a citizen of the United States of America, residing at Antonia, in the parish of Grant and State of Louisiana, have invented new and useful Improvements in Frame Construction, of which the following is a specification.

This invention relates to improvements in frame construction and has particular application to glass holding frames.

In carrying out the present invention, it is my purpose to provide a frame wherein the panes of glass may be held in position without resorting to the use of putty and the like and which will be constructed in such manner that the glass may be readily inserted in and removed from the frame without necessitating dismantling thereof.

Furthermore, I aim to provide a frame which will embody the desired features of simplicity, efficiency, durability and convenience and which may be manufactured and marketed with economy of cost.

With the above and other objects in view, the invention consists in the construction, combination and arrangement of parts hereinafter set forth in and falling within the scope of the claim.

In the accompanying drawing; Figure 1 is a front elevation of a glass holding frame constructed in accordance with the present invention. Fig. 2 is a horizontal sectional view on the line 2—2 of Fig. 1. Fig. 3 is a fragmentary vertical sectional view on the line 3—3 of Fig. 1. Fig. 4 is a similar view on the line 4—4 of Fig. 1.

In the present instance, I have shown my invention as embodied in a window sash. It is to be understood, however, that the invention in its useful application is not limited to this particular purpose, as the same may be incorporated in the construction of transoms, doors and other frames equipped with glass and the like transparent panels.

Referring now to the accompanying drawing in detail, the letter A designates the sash of the window as an entirety. This sash, in the present instance, is composed of the stiles 1 and 2, the top and bottom end rails 3 and 4 having their opposite ends suitably connected to the adjacent ends of the stiles, and the vertical and transverse mullions 5 and 6 respectively intersecting each other approximately centrally of the side rails and stiles of the frame and having

the opposite ends thereof connected in any suitable manner, as by mortise and tenon joints, to such side rails and stiles, the mullions being also suitably secured to each other at the point of intersection. 60

The opposite side edges of the mullions 5 and 6 are rabbeted as at 7 and the side walls of such rabbeted portions are undercut as at 8 to receive cushions or buffers 9 formed of elongated rubber strips or other suitable material. The adjacent or confronting side edges of the side rails 1 and 2 are also rabbeted as at 10, the side walls of the last-mentioned rabbeted portions being undercut as at 11 to receive buffers or cushions 12 formed of strips of rubber or the like. Strips 13, 13, each of a length equal to that of the side rails 1 and 2, are fastened, as by screws 14, to the sides of the end rails 1 and 2 onto which the rabbeted portions open and overlie such rabbeted portions and co-operate with the walls thereof to form grooves 15. Similarly, strips 16, 16, each of a length commensurate with that of the mullions 5 and 6, are fastened, as by screws 17, to the sides of the mullions onto which the rabbeted portions open and co-operate with the walls of such rabbeted portions and overlap the latter to form grooves 18. 75 80 85 90 95

These strips 16, 16, as shown in Fig. 1 of the drawing, are preferably formed of two sections having the meeting ends thereof pointed so that when the alining sections of one strip are assembled, laterally opening V-shaped seats are provided for the reception of the pointed extremities of the sections of the strip on the other mullion. It will be seen that the grooves 15 and 18 which are in open communication with one another form open ended pathways for receiving a pane of glass. 100 105 110

In order to close each open ended pathway for the glass so as to securely hold the

latter in the frame, a securing strip 22 is applied to the face of each end rail 3, 4 adjacent to the grooves and is equipped with an overhanging lip 23 disposed within the 5 groove 19 in the outer edge of the respective end rail and of a configuration corresponding to that of said groove, the lower end of the securing strip being rabbeted as at 24 to receive the adjacent edge of the glass, the 10 side wall of the rabbeted portion 24 forming, with the adjacent portion of the wall of the respective end rail, a groove, the opposite side walls of which are undercut as at 25, 25 to receive the buffers 26. The opposite ends of the vertical mullion are preferably rabbeted, as illustrated, and overlap the securing strip at the center thereof, a fastening screw or the like 27 being passed through the walls of the rabbeted extremities 15 of the mullions and through the respective securing strips and end rails.

In the embodiment of my invention selected for illustrative purposes, it will be noted that the frame presents, in effect, a 20 plurality of glass receiving frames, the contiguous or inner side edges of which are formed with communicating grooves which provide an open ended pathway for the glass, the open end of the pathway being 25 closed by a removable securing strip by means of which the glass may be held within the frame and which may be detached to enable the glass to be withdrawn from the frame in the event of fracture or breakage.

From the foregoing description taken in 35 connection with the accompanying drawing, the construction and manner of employing my invention will be readily apparent. It will be seen that I have provided a frame wherein panes of glass may be held without necessitating the use of putty and the like and from which the glass may be readily removed in the event of the same being broken. 40

While I have herein shown and described one preferred form of my invention by way 45 of illustration, I wish it to be understood that I do not limit or confine myself to the precise details of construction herein described and delineated, as modification and variation may be made within the scope of 50 the claim and without departing from the spirit of the invention.

I claim:

In a window sash in which the stiles are provided with pane grooves, an end rail having one face flush with the side walls of the said pane grooves and provided with a V-shaped groove in the outer side thereof, and a securing strip forming a closure for the said pane grooves and provided with an 55 overhanging lip disposed within said V-shaped groove.

In testimony whereof I affix my signature in presence of two witnesses.

WM. CURTIS LINDER.
